UNITED STATES PATENT OFFICE.

WILLIAM R. MATTHEWS, OF PITTSBURG, PENNSYLVANIA, ASSIGNOR TO THE McCONWAY & TORLEY COMPANY, OF PITTSBURG, PENNSYLVANIA, A CORPORATION OF PENNSYLVANIA.

DRAFT-GEAR FOR RAILWAY-CARS.

No. 922,708.

Specification of Letters Patent.

Patented May 25, 1909.

Application filed September 11, 1907. Serial No. 392,331.

To all whom it may concern:

Be it known that I, WILLIAM R. MATTHEWS, a citizen of the United States, residing at Pittsburg, in the county of Allegheny and State of Pennsylvania, have invented 5 certain new and useful Improvements in Draft-Gear for Railway-Cars; and I do hereby declare the following to be a full, clear, and exact description of the invention, 10 such as will enable others skilled in the art to which it appertains to make and use the same.

My invention relates to the construction 15 of draft gear for railway cars, and has for its object the production of simple and efficient draft appliances which shall enable cars to pass around very sharp curves without subjecting the car platform to excessive lateral strains. The construction and arrangement 20 of the several parts of my device are such that the coupler constantly tends to assume its normal position in the longitudinal axis of the car.

In the drawings chosen for the purpose of 25 illustrating my invention, the scope whereof is pointed out in the claims, Figure 1 is a plan view of a draft gear embodying my invention and of the adjacent parts of the car underframing, the parts being illustrated in the position they assume 30 when the car is standing on a straight track; Fig. 2 is a view similar to Fig. 1, but illustrating the relative positions occupied by the several parts of the draft gear when cars 35 sixty feet in length are passing around a curve of thirty-five feet radius; Fig. 3 is a view, partly in side elevation and partly in central section, of the devices illustrated in Fig. 1; Fig. 4 is an enlarged, vertical central 40 section of the yoke or spring pocket and portions of its connections; and Fig. 5 is a detail section taken on the line 5—5, Fig. 1.

Like symbols refer to like parts wherever they occur.

45 I will now proceed to describe my invention more fully, so that others skilled in the art to which it appertains may apply the same.

In the drawings, 1 indicates the coupler 50 head which, if desired, may be rigidly connected to the coupler shank or draft stem 2, but which is preferably pivoted on said draft stem in a manner such that the two parts may have a relative movement under the 55 control of suitable spring mechanism by

which said head is normally centralized with respect to said stem. The rear end of the draft stem 2 is attached to the yoke or spring-pocket 3 in any manner which will permit the usual draft spring 4 to be compressed in buffering. In the construction illustrated, this purpose is accomplished by forming said yoke 3 with oppositely disposed longitudinal slots 5, through which, and through the rear end of the draft stem 2, a 60 bolt 6 passes. It is preferred not to depend upon the bolt 6 for transmitting draft strains from the draft stem 2 to the yoke 3, but to form the inner end of said draft stem with shoulders which are engaged by the inturned 65 ends of the yoke in a well known manner.

The draft spring 4, which is located within the yoke 3, is seated at its rear end upon said yoke and at its forward end bears upon a follower 7 that abuts the rear end of the 70 draft stem 2. The follower 7 is restrained from forward movement by the tail bolt 8, which is pivotally attached to the abutment member 9 and which passes through the yoke 3, the draft spring 4 and the said follower 7. The rear end of the draft stem 2 is cored to receive the forward end of the tail-bolt during a buffering operation of the parts, and the abutment casting 9 is preferably 75 formed with separated lugs or flanges 10 between which the said tail-bolt is pivoted by a bolt 11. The abutment casting 9 thus both 80 supports and confines the rear end of the draft gear.

The abutment member 9 may be attached 85 to the car underframing either by bolts, as shown, or in any other suitable manner. The socket formed in the member 9 for the reception of the enlarged end of the tail-bolt 8 is constructed with outwardly diverging 90 walls, as shown in dotted lines at 12, in order to permit the lateral swinging of the draft appliances, and the outer faces of the pivot lugs 10, with which the rear end of the yoke 95 is preferably arranged to engage when buffering, are suitably rounded to also permit lateral oscillation of the draft rigging devices. If desired the entire buffering strain 100 may be transmitted to the abutment casting 9 through the tail-bolt 8, as the enlarged 105 head of the latter bears against that end of the yoke upon which the draft spring 4 is seated, but as buffering strains are normally so much greater than draft strains it is preferred to support the rear end of the yoke 110.

directly by the abutment casting 9, as well as through the tail-bolt 8.

13 indicates a spring - cushion buffer which is mounted on the end of the car so that it may reciprocate in a horizontal plane. In the drawings the end of the car platform and the buffer are both shown as of curved form, since my invention is illustrated as applied to a type of car that is commonly in use upon lines having exceedingly sharp curves, but it is to be understood that this invention is equally applicable to platforms and buffers of other forms. The buffer 13 is preferably formed with a buffer plate 14 and a foot plate 15 which are integrally united, the latter extending rearwardly immediately beneath the foot-plate housing 16 which is secured to the car platform. At equal distances from the center of the buffer 13, and pivotally attached to said buffer, as at 17, are rearwardly extending buffer stems 18 that are supported from the car framing in a manner to permit reciprocation longitudinally of the car. The forward portion 25 of each buffer stem is preferably square in cross-section, while the rearward portion is preferably round and of less cross-sectional area. The shoulders thus formed upon the buffer-stems 18 operate as stops for the ring-washers 19, one of which is applied to each of said stems. Surrounding the rear portion of each buffer-stem is a buffer spring 20 that is interposed between the appropriate ring-washer 19 and a buffer stop 21 which is secured to the underframing and which forms a support and guide for the reciprocating buffer-stem. The forward portion of each buffer stem 18 is guided by its respective buffer-guide or thimble 22, the latter being set in a mortise formed in the end sill of the car platform.

Pivottally attached to the buffer 13 in the longitudinal axis of the car, by means of a bolt 23 or in other suitable manner, is an equalizer member 24 the rear end of which is attached to the coupler draft stem 2 in front of the draft spring 4 by a pin and slot connection. The pin 25 of this pin and slot connection is preferably mounted on the draft stem 2 a short distance in advance of the forward end of the yoke 3, while the slot 26 is preferably formed in the equalizer member 24, said slot being sufficiently long to let the bolt 25 move forward under draft strains 55 without communicating such strains to the equalizer.

For the purpose of supporting the coupler during its lateral swinging movements, it is preferred to employ a curved supporting rail 60 27 which is suspended by bolts, or in other suitable manner, from the under side of the car platform.

The mechanism for centralizing the coupler head 1 with respect to the draft stem 2 65 may be of any desired character, the con-

struction illustrated in the drawings for accomplishing this purpose consisting of a spring 28 which is interposed between flanged spring cups 29 that bear at their outer ends upon the lateral walls of the coupler head. The spring and spring cups are mounted in a transverse aperture formed in the draft stem 2, and the latter is provided with lugs or flanges 30 by which one of the spring cups is forced toward the other whenever the coupler head 1 is displaced from its normal central position. The compression thus induced in the spring 28 by the approach of the spring cups will cause the coupler head to return to a central position with respect to the draft stem 2 whenever the force acting on the spring cups is withdrawn, as will be readily understood.

Any suitable mechanism may be employed for actuating the lock 31 to permit cars to be uncoupled, but it is preferred to employ for this purpose a coupler release rigging such as that described in my pending application Serial Number 375,066, filed May 22, 1907.

The construction and arrangement of the several parts of the draft-gear being substantially such as hereinbefore pointed out, the operation of the mechanism will be as follows:

Assuming the parts to be in normal position, as illustrated in Figs. 1, 3 and 4 of the drawings, a draft strain upon the coupler head 1 exerted in the longitudinal axis of the car will cause the draft stem 2 and yoke 3 to move forward, and as the follower 7 is restrained from forward movement by the tail-bolt 8 the draft spring 4 will be compressed between said follower and the rear end of the yoke 3. During this forward movement of the coupler, the buffer devices are unaffected, since the pin 25 by which the equalizer 24 is connected to the draft stem 2 merely moves forward in the slot 26.

When a buffing force is applied to the coupler in the longitudinal axis of the car, the draft stem 2 forces the follower 7 rearwardly, and as the yoke 3 and tail-bolt 8 are prevented from retreating by the abutment casting 9 the spring 4 is compressed. The relative movement of the yoke 3 and draft stem 2 necessary to accomplish the compression of the spring 4 in buffing is permitted by the pin and slot connection between said yoke and draft stem. If the buffers 13 on adjacent cars are not already in contact when this buffing operation is begun, the draft stem 2, acting through the bolt 25 and equalizer 24, will transmit a portion of the buffing force to the said buffer 13, which will, in turn, transmit it to the buffer springs 20 through the medium of the buffer stems 18, ring washers 19 and buffer stops 21.

When the coupler is laterally displaced from its normal position in the longitudinal

axis of the car, the equalizer member 24 is likewise displaced and the point of attachment of the two members no longer lies in the line connecting the points of pivotal attachment of the draft stem and equalizer to the underframing and buffer, respectively. Since this lateral displacement of the connecting point of the equalizer 24 and draft stem 2 tends to cause the point of attachment of said equalizer with the buffer 13 to approach the pivot pin 11 carried by the abutment casting 9, and since the equalizer 24 is practically inextensible while the draft spring 4 permits the distance between the pivot pins 11 and 25 to be increased, it results that the lateral displacement of the coupler causes a rearward motion of the buffer 13 and a consequent compression of the buffer springs 20, and also causes a separation of the said pivot pins 11 and 25 with a consequent compression of the draft spring 4. It will be apparent that as soon as the force causing the lateral displacement of the coupler is withdrawn, the springs 4 and 20 will reassume their respective normal lengths, and in so doing will return the coupler and equalizer to their normal positions in the longitudinal axis of the car.

Not only are the draft spring 4 and buffer springs 20 compressed when the coupler is laterally displaced, but the coupler head centering spring 28 is also compressed, as heretofore explained.

Having thus described my invention, what I claim and desire to secure by Letters Patent is:

1. In a device of the character indicated, the combination with a coupler which is provided with means whereby it may be pivotally connected to the body of a car, of buffer mechanism, a draft spring arranged to resist a lateral displacement of said coupler, and means operatively connecting said coupler and said buffer mechanism whereby said buffer mechanism constantly tends to centralize said coupler.

2. In a device of the character indicated, the combination with a coupler which is provided with means whereby it may be pivotally connected to the body of a car in a yielding manner, of buffer mechanism, and buffer controlled means whereby the coupler is centralized after being displaced from its normal position in the longitudinal axis of the car, said buffer mechanism being unaffected by draft forces applied to the coupler in the longitudinal axis of the car.

3. In a device of the character indicated, the combination with a coupler which is provided with means whereby it may be pivotally connected to the body of a car, of buffer mechanism, which is unaffected by forward longitudinal movements of the coupler, and means whereby the lateral displacement of

the coupler from its centralized position is resisted by the said buffer mechanism.

4. In a device of the character indicated, the combination with a coupler which is provided with means whereby it may be pivotally connected to the body of a car, of a draft spring arranged to resist a lateral displacement of said coupler, a spring cushioned buffer, and means whereby the lateral displacement of the coupler from its centralized position is resisted by said buffer.

5. In a device of the character indicated, the combination with a coupler which is provided with means whereby it may be pivotally connected to the body of a car in a yielding manner, of a draft spring, a spring cushioned buffer, and an equalizer member which is pivotally connected to said buffer and to said coupler, said equalizer member operating to cause said buffer to move rearwardly when the coupler is displaced from its centralized position.

6. In a device of the character indicated, the combination with a coupler which is provided with means whereby it may be pivotally connected to the body of a car in a yielding manner, of a draft spring, a spring cushioned buffer which operates to maintain the coupler in a centralized position, and an equalizer member which is attached to said coupler and to said buffer in a manner which permits draft strains acting in the longitudinal axis of the car to be entirely absorbed by said draft spring.

7. In a device of the character indicated, the combination with a coupler which is provided with means whereby it may be connected to the body of a car in a yielding manner through the medium of a draft spring, of a draft spring, a yoke operating upon said draft spring and relatively movable longitudinally with respect to said coupler, a spring cushioned buffer, and means whereby the lateral displacement of the coupler from its centralized position is yieldingly resisted by said buffer.

8. In a device of the character indicated, the combination with a coupler head, of a draft stem which is pivotally attached to said head and to the car body, a draft spring, a yoke operating upon said draft spring and having a slidably connection with said draft stem, a buffer having buffer stems attached thereto, springs for resisting the movement of said buffer stems in one direction, and an equalizer member interposed between said buffer and said draft stem and operating to centralize said coupler.

9. In a device of the character indicated, the combination with a coupler head having a rearwardly extending draft stem which is pivotally attached to the body of a car in a yielding manner, of a buffer, buffer stems attached to said buffer, springs operated upon

by said buffer stems, and an equalizer member which is pivotally attached to said buffer and to said draft stem, said buffer springs being compressed by a lateral dis- 5 placement of the said draft-stem in either direction.

10. In a device of the character indicated, the combination with a coupler which is provided with means whereby it may be pivotally connected to the body of a car in a yielding manner, of a draft spring, and a pivotally mounted equalizer member connected with said coupler, said equalizer member operating to cause a compression of said 15 draft spring when the coupler is displaced laterally.

11. In a device of the character indicated, the combination with a coupler, of a yoke which is relatively movable longitudinally 20 with respect to said coupler, means acting 25 upon said yoke for yieldingly and pivotally connecting said coupler to the car body,

and an equalizer member which is connected to said coupler and is relatively movable longitudinally with respect there- 25 to said equalizer member operating to centralize said coupler.

12. In a device of the character indicated, the combination with a coupler which is provided with means whereby it may be pivotally connected to the body of a car in a yielding manner, of a laterally displaceable equalizer member the rear end of which is connected to the coupler and the front end of which is pivotally attached to a movable 30 spring-cushioned support, and a movable spring-cushioned support attached to said car.

In testimony whereof I affix my signature, in presence of two subscribing witnesses. 40
